FURNACE STRUCTURE

Edward M. Kane, Ithaca, N. Y.

Application August 22, 1941, Serial No. 407,963

2 Claims. (Cl. 110—75)

The present invention relates to improvements in furnace structures.

The primary object of the invention is to provide means for feeding air to the fire box of a furnace from the opposite walls of the fire box to complete combustion and to eliminate smoke and volatile gases during firing operation.

A further object of the invention is to provide a furnace structure with sinuous air passage-ways in the opposed side walls of the furnace fire box so that jets of air may be projected above the fire to complete combustion during the firing operation and to close a portion of the passage-ways during the normal operation of the furnace.

A still further object of the invention is to provide a furnace fire box structure with sinuous passages in the side walls thereof for pre-heating air so that the air when projected over the fire box will more readily complete combustion of the volatile gases during firing operation and to provide automatic means for closing off or reducing the admission of air to the fire box upon the lapse of a predetermined time interval.

Other objects and advantages of the invention will become apparent during the course of the following description of the accompanying drawings, wherein,

Figure 1 is a side elevational view of a furnace structure embodying the invention and illustrating the furnace broken away through the fire box area to illustrate in detail the arrangement of the air feeding compartment;

Figure 2 is a front elevational view of a furnace structure showing portions broken away to further illustrate in detail the location of the air jet compartments and the general arrangement of the air feeding ducts; and

Figure 3 is a vertical cross-sectional view taken on line 3—3 of Figure 1, looking in the direction of the arrows, illustrating in detail the construction of one of the air feeding chambers.

In the drawings, wherein for the purpose of illustrating the invention and wherein like reference characters will be employed to designate like parts throughout the same, the reference character 5 will generally be employed to designate a furnace structure having a pair of brick opposed side walls 6, an end wall 7 and a front wall 8.

A boiler 9 is supported by the rear brick wall 7, while the opposite end is supported on a ledge 10 carried by the front wall 8. The forward portion of the furnace structure is pro-

vided with a fire box chamber 11 confined between the side and front walls and a bridge fire box wall 12.

The furnace gases pass rearwardly of the furnace structure over the fire box bridge wall 12 and return through the boiler flue pipes in the boiler 9 and are carried off by means of a stack, as at 13.

Fire doors 14 are provided in the front wall 8 beneath which is located ash doors 15 and access may be had to the boiler flues for the purpose of cleaning the same through doors 16 carried by the front wall of the furnace 8, above fire doors 14.

15 A top wall 17 completes the furnace structure and a refractory lining 18 is placed on the side walls 6, as well as the front, rear and top walls 8, 7 and 17. The refractory lining may be of usual construction and is intended to withstand 20 high temperatures. A boiler feed pipe 19 is provided for supplying the boiler 9 and a clean-out discharge door 20 is provided in the rear wall 7 for removing foreign matter deposited on the floor of the furnace from the boiler tubes.

25 The invention comprises a pair of oppositely disposed air feeding chambers 21 which are located on opposite sides of the fire box 11 and are mounted in the refractory side wall linings 18. Each air feeding chamber 21 is rectangularly formed and extends longitudinally of the furnace structure between the front wall 8 and the fire box bridge arch 12 immediately above the grate bars 22.

30 Each air feeding chamber 21 is provided with side walls 23 connected at the upper end by a top wall 24 and at the lower end by means of a bottom wall 25. End walls 26 complete the structure.

35 One of the side walls 23 is presented to the fire box 11 and the other wall is embedded in the refractory side wall lining 18, as shown in Figure 3. The walls 23 which are presented to the fire box are provided with perforations 28 and 29 arranged in parallel rows, extending 40 throughout the entire length of the air feeding chamber 21.

45 Connecting the side walls 23 of the rectangular box-like structure, is a partition 30 which extends from one of the end walls 26 and terminates short of the opposite end wall to provide a passageway 31 extending the entire length of the air feeding chamber where it communicates with a vertical passageway 32 formed by means of a vertically positioned partition wall 50 33 connecting the side walls 23 and terminating

a distance short of the bottom wall 25 and top wall 24.

A horizontally arranged partition 34 extends from the vertical partition 33 toward the front of the furnace and terminates a short distance from the end wall 26, thereby providing a horizontal passageway 35 so that the air admitted at one end of the air feeding chamber will be caused to travel a sinuous path and become pre-heated before passage to the fire box through the horizontal rows of apertures 28 and 29.

Extending longitudinally of the air chamber 21 is a partition 36 which connects the side walls 23 and is located between the partitions 30 and 34 so that one end will connect with the vertical partition 33 while the opposite end will terminate a distance short of the end wall 26. The partition 36 divides the parallel rows of apertures 28 and 29 so that a compartment or air passageway 37 and 38 will be provided for each row of apertures.

Pipe sections 38^a are connected to the forward end of each air feeding chamber 21 and one of the pipe sections 38^a is provided with an elbow 39 for connection with a pipe line 40 which connects with the other pipe section 38^a as by means of a T-union 41. A pipe 42 is connected to a pipe 43 by means of an elbow 44 and the pipe 43 is connected to the exhaust 45 of an air blower 46, whereby a constant air feed will be supplied to each of the air feed chambers 21.

Formed in the front wall 8 of the furnace structure is a cut-away portion 47 so that a sliding gate 48 may pass through one of the end walls 26 and contact the central partition plate 36 to cut off the lower passageway 38, during normal operation of the furnace. The gate 48 slides in a longitudinal slot in the end wall 26 and communicates with a similarly shaped slot in a reduced portion of the front wall 8 by means of the cavity 47. A slide rod 49 has one end connected to the sliding gate 48 and the opposite end attached to a bell crank 50 pivotally attached to a suitable bracket 51 secured to the front wall 8.

A time controlled latch release member 52 is mounted on the front wall 8 adjacent the top of the furnace and is provided with a control lever 53 which is adapted to be tripped to allow the downward movement of the lever 53 after the lapse of a predetermined time interval so that the lever 53 will raise the slide rod 54 which connects the lever 53 and one arm of the bell crank lever 50. A weighted member 55 may be slidably attached to the bell crank lever 50 so that the bell crank lever will rotate when the latch 53 is released to move the gate 48 to its closed position.

During normal operation of the air feeding system, the air will pass from the blower 46 to each of the air feeding chambers 21 and will pass the length of the chamber through the passageway 31 whereby the air will return and pass in the opposite direction through the passage 35 to the front wall 26 and into the passageway 37 so that the air will pass over the fire box 11 through the apertures 28 and support combustion of the unburned gases before the same pass to the boiler.

During firing operation, and when coal is fed to the fire box, a great volume of volatile gases are created and during this period, it is intended to open the gate 48 manually by lifting upwardly on one arm of the bell crank 50 so that an

additional supply of air will be fed to the fire box through both series of apertures 28 and 29.

After a suitable predetermined time lapse, the latch 53 will be released and will allow the gate 48 to close and the furnace to operate under normal conditions with air being fed to the fire box through only one series of apertures 28.

By controlling the air feed, as above mentioned and described, smoke may be eliminated to a great degree, with the result that the boiler flues will be kept in a clean condition, thereby increasing the efficiency of the furnace and the burned gases will create additional heat, thereby increasing the efficiency of the furnace operation.

It is to be understood that the form of the invention herewith shown and described is to be taken as the preferred embodiment of the same and that various changes in the shape, size and arrangement of parts may be resorted to without departing from the spirit and scope of the invention as claimed.

I claim:

1. A furnace structure having a fire box, an elongated air chamber at each side of the fire box, each chamber comprising a closed casing having one side exposed to the fire box, a series of vertically spaced horizontal partition walls in the casing terminating in spaced relation to the rear end of the casing and connected by a vertical wall forming a circuitous passageway in the casing around the horizontal partitions, an air inlet to the lower side of the passageway adjacent the front of the casing, the lower one of said partitions extending to the front end of the casing and the superposed partitions terminating in spaced relation to said front end of the casing for the entry of air to the spaces between the partitions, and the side of the casing exposed to the fire box having aligned rows of openings therein registering with the spaces between the partitions whereby heated air is delivered from the casing into the fire box to promote combustion and consume smoke.

2. A furnace structure having a fire box, an elongated air chamber at each side of the fire box, each chamber comprising a closed casing having one side exposed to the fire box, a series of vertically spaced horizontal partition walls in the casing terminating in spaced relation to the rear end of the casing and connected by a vertical wall forming a circuitous passageway in the casing around the horizontal partitions, an air inlet to the lower side of the passageway adjacent the front of the casing, the lower one of said partitions extending to the front end of the casing and the superposed partitions terminating in spaced relation to said front end of the casing for the entry of air to the spaces between the partitions, and the side of the casing exposed to the fire box having aligned rows of openings therein registering with the spaces between the partitions whereby heated air is delivered from the casing into the fire box to promote combustion and consume smoke and a horizontal gate carried by the front end wall of the casing above the lower partition adapted to be moved into contact with the adjacent end of the lowest shortened partition wall to divide the circuitous passageway for shutting off one row of said openings for controlling the volume of air passed over the fire box.

EDWARD M. KANE.
